UNITED STATES PATENT OFFICE

107,061

DESIGN FOR A DRESS ENSEMBLE

Philip Wenett, New York, N. Y.

Application October 22, 1937, Serial No. 72,360

Term of patent 3½ years

To all whom it may concern:

Be it known that I, Philip Wenett, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear jacket portion is conventional.

I claim:

The ornamental design for a dress ensemble, substantially as shown and described.

PHILIP WENETT.
